UNITED STATES PATENT OFFICE.

EARL L. PRICE, OF OAKLAND, CALIFORNIA.

CAN-FILLING MACHINE.

1,290,656.

Specification of Letters Patent.

Patented Jan. 7, 1919.

Application filed September 11, 1917. Serial No. 190,853.

To all whom it may concern:

Be it known that I, EARL L. PRICE, a subject of the King of England, residing at Oakland, in the county of Alameda and State of California, have invented new and useful Improvements in Can-Filling Machines, of which the following is a specification.

This invention relates to a machine for filling cans, jars, and the like with liquids, and more particularly to a valve by which the filling operation is controlled.

One of the objects of the present invention is to provide a simple, compact filling machine of the continuous rotary type, whereby cans containing fruit or like material to be preserved may be filled to a predetermined level with syrup or other liquid without waste or dripping; and also to provide a plurality of charging valves to permit the machine to operate simultaneously upon a number of cans as they are passing through the machine. Another object of the invention is to provide a novel form of automatic charging valve which will permit each can to be rapidly and uniformly filled and which will simultaneously permit a perfect venting or removal of air while the filling operation is taking place. Further objects will hereinafter appear.

The invention consists of the parts and the construction and combination of parts as hereinafter more fully described and claimed, having reference to the accompanying drawings, in which—

Figure 1 is an enlarged, central, vertical section through one of the charging valves.

Figs. 2, 3 and 4 are perspective views of different parts of the valve shown in Fig. 1. The construction of the syrup dispensing or charging valve 7, through which the syrup flows while the cans are being filled, is as follows:

Referring to Figs. 3, 4, 5 and 6, 9' indicates, in general, a valve cage which is adapted to be inserted through the bottom of the tank. The lower end of the cage is provided with a peripheral flange 10 which engages the bottom face of the tank shown in fragment at 6 and screws 11 passing through said flange secure the cage in position when inserted; the face between the

bottom of the tank and the flange 10 being finished to permit the formation of a tight joint when insertion is made. Formed in the upper end of the cage is a central hub member 12 which is supported or carried by means of a plurality of arms 13, and formed in the sides of the cage is a plurality of ports or openings 14 through which syrup contained in the tank is permitted to flow.

Slidably mounted interiorly of the cage is a cylindrical member 15, on the lower end of which is secured the valve proper. This valve is constructed by forming a large flange 16 on the lower end of the cylinder 15 and an annular shoulder 17 for the reception of a rubber gasket 18. Formed in the lower end of the cylinder 15 is an annular groove 19 and placed in said groove is a packing ring 20 which forms a tight joint between the cylinder and the cage 9 to prevent leakage. Extending through the hub 12 is a threaded hollow valve stem 21, and secured on the lower end of said stem is a head member 22 which is provided with a hollow central space 23 and an annular downwardly projecting flange 24. The upper face of the head member is provided with an annular seat 25 for the reception of the valve and the lower face, together with the flange 24, is provided with a series of perforations 26 which serve as an escape for the air when a can is being filled.

Secured on the upper end of the valve stem 21 is a nut 27 and interposed between said nut and a follower head 28, engaging the upper cylindrical end of the valve, is a coil spring 29. This spring exerts its pressure upon the follower head 28 and the valve and thereby normally holds it in engagement with the annular seat 25 formed on the head 22. Discharge of syrup from the tank can only take place when the valve is raised into the position shown in Fig. 1 or when a can is in position. The construction of the several charging or dispensing valves is identical and as they all protrude through the bottom of the tank it can readily be seen that the syrup is at all times standing within the valve and will freely discharge the moment it is opened. Syrup may be delivered to the tank through a pipe from any suitable source of supply and a float valve, or any other suit-

able means, may be provided for maintaining a constant level within the tank.

In actual operation, the can is moved into engagement with the rubber lined face 18 of 5 the valve, thus sealing the can. A further movement forces the valve away from its seat 25, as shown in Fig. 1, and thereby permits the syrup from the tank to flow through the communicating ports 14, formed in the 10 cage, and the valve 15 in the direction of the arrows. The syrup then passes over the head 22 and the valve seat 25 and at this point discharges through the annular passage formed between the flange 24 and the 15 upper end of the can.

The syrup on entering the can drives out the air contained and this escapes through the perforations 26 and 26' into the chamber 23 and from here passes through the hollow 20 valve stem 21 directly to the atmosphere, the height of the stem 21 being such that it passes a considerable distance above the syrup level within the tank. Plenty of time is allowed to fill each can and also to permit the 25 syrup or liquid dispensed to back up through the air chamber 23 and enter the tube 21. This insures a perfect removal of all air and also insures a uniform filling of each can as the liquid rising in the stem 21 will naturally 30 seek the level of the contents of the tank.

The closing of the valve is accomplished when the can is lowered. This receding movement permits the spring 29 to exert its pressure on the follower head and force the 35 valve against the seat 25. The flow of syrup is in this manner stopped and a perfect seal is formed between the valve and the seat 25, thus preventing leakage or dripping at the time when the can is removed.

40 The construction of the head member 22 is one of the most important features of the valve proper; that is the position of the head member is such that it enters the can and serves as a displacing member. A can when 45 completely filled causes the syrup to back up through the venting tube until this level is obtained. A great portion of this syrup would flow back into the can the moment the valve closes and the can recedes therefrom. 50 This extra supply of syrup is, however, taken care of by the head 22 as it served as a displacing member while in the can.

The actual operation that takes place when the valve is closing is first to force a 55 part of the syrup up through the venting tube as the valve acts as a plunger of a pump when closing down against the seat. Only a small amount of syrup is discharged or spit out through the valve stem while the valve 60 closes, but the major portion of it drains back into the can as the plunger recedes. The amount of liquid or syrup displaced by the head 22 is thus replaced by the returning liquid from the stem 21 and the chamber 23

and each can, when leaving the machine, is, 65 therefore, practically filled and a predetermined level, so to speak, is obtained in each can regardless of the amount of fruit contained when received by the machine. The desired liquid level in the can, when it is 70 discharged from the machine, may be varied by increasing or decreasing the size of the head 22 or by varying the size of the venting passage 21 and the air chamber 23.

The annular flange 24 formed on the head 75 is also of importance as it permits the fruit, for instance peaches and the like, to be forced down into the can without injuring the same while the filling operation is taking place and it also serves as a trap to collect 80 the escaping air.

I further wish it understood that various changes in form, proportions and minor details of construction may be resorted to within the scope of the appended claims and that 85 I do not wish to limit myself to the specific design and construction here shown.

Having thus described my invention, what I claim and desire to secure by Letters Patent is—

1. In a can filling machine, a tank, a dispensing valve including a cage in the tank, a central hub at the upper end of the cage, a valve having a stem slidable in the cage below said hub, a hollow stem secured to the hub of the cage, a head member secured to the lower end of said hollow stem and having a horizontal hollow chamber communicating with said hollow stem, said head member having vertical perforations extending into said hollow chamber, a laterally apertured flange depending from said head in surrounding relation to said vertical perforations, an abutment on the upper end of the hollow stem, a follower head surrounding said hollow stem and seated on the upper end of the valve stem, and a spring surrounding the hollow stem and engaged at its ends with said abutment and follower, said cage and valve stem having registering ports and said valve being normally held by the spring seated on the upper face of the head. 100

2. In a can filling machine; a tank, a cage in the tank having a hub at its top part, spaced arms to rigidly secure the hub to the 115 cage at the center of the latter, a hollow air venting stem rigidly secured to the hub and extending below the tank, a valve having a stem slidable in the cage below the hub thereof, a head on the venting stem having a seat for said valve, an abutment on the venting stem, a follower formed to straddle said arms of the hub and bearing against the upper end of the valve stem, and a spring on the venting stem engaged with said follower 120 and abutment.

3. In a can filling machine, a tank, a cage in the tank, an air venting stem, means to

rigidly secure said stem to said cage with the ends of the stem extending above and below the respective cage ends, a head on the stem, a valve having a stem slideable in the cage and seating on said head, a follower surrounding said venting stem and seating on said valve stem, an abutment on the upper end of the venting stem, and a coil spring surrounding the venting stem and en-

gaging said abutment and seating on said 10 follower.

In testimony whereof I have hereunto set my hand in the presence of two subscribing witnesses.

EARL L. PRICE.
